CASTING MACHINE

Donald H. Garth, Chicago, Ill.

Application August 3, 1938, Serial No. 222,737

8 Claims. (Cl. 22—57)

This invention relates to a casting machine. The particular embodiment which I shall herein illustrate and describe is a machine for die casting metal objects.

One of the main objects of the invention is to provide a casting machine which is operable expeditiously to provide a plurality of good castings of the same shape or in different shapes at the same time, and a machine in which an unlimited variation in the shapes of any number or all of the plurality of castings produced at the same time may be readily accomplished.

It is a further object to reduce or substantially eliminate heat loss from the molten metal in its delivery from the molten metal container through the gate and runner means to the mold means, so as to prevent chilling or solidification of the molten metal in the gate or runner means or elsewhere in its passage to the mold means, and to assure that the molten metal is delivered into the mold means in the desired molten condition completely to fill the mold means and produce good homogeneous castings at all times.

The maintenance of the metal in molten condition in its passage through the gate and runner means eliminates cleaning of gates and runners from the finished work and clogging of the metal in its passage to the mold means. The master mold plates are preferably arranged so that the molten metal will drain from the runners and gates when the mold plates are parted, and the base section of the machine is preferably formed to hold a removable tray or crucible for catching the overflow or waste metal in operation.

It is a further object of the invention to provide an improved displacement method of delivering the molten metal from the molten metal container to the mold means. In the illustrated embodiment, this displacement method, in conjunction with the arrangement of the mold plates, results in utilization of the force of gravity to fill the molds without the use of forced air or the like, and permits accurately controlling the amount of metal delivered to the mold plates in accordance with that required properly to fill the molds. The lead for delivering the molten metal from the container therefor to the gate means of the mold plates is preferably enclosed to reduce oxidation of the metal.

It is also an object to provide an improved master mold plate for not only holding the replaceable molds or mold holders, but also adapted for artificially cooling the molds without loss of heat from the molten metal in its passage through the gate and runner means of the mold plate. If

desired, the mold plate may be utilized to apply heat to the molds to maintain the metal in the molds in molten condition until the desired filling of the molds is accomplished.

5 Another object is to provide means for adjusting the casting molds in the master mold plates for the purposes to be hereinafter described, and for locking the molds in adjusted position; also adjusting means for securing perfect fitting of the matched mold plates and the molds carried thereby, and guide means for guiding the plates into perfect fit and for preventing relative sagging of the plates.

15 Another object is to provide a casting machine of simple and inexpensive construction that may be operated conveniently, and an improved carriage arrangement and movement imparting means for the relatively movable master mold plate.

20 Further objects and advantages of the invention will appear from the following detailed description, taken in connection with the accompanying drawings, in which:

Figure 1 is a side elevational view, partially in section, of a casting machine embodying the present invention;

Figure 2 is a vertical section taken on the line 2—2 of Figure 1;

Figure 3 is an end view of the casting machine looking from the left hand end, as viewed in Figure 1;

Figure 4 is a horizontal section taken on the line 4—4 of Figure 2;

Figure 5 is a fragmentary detail section taken on the line 5—5 of Figure 4;

Figure 6 is a back side view of one of the master mold plates, showing the means for delivering a cooling medium thereto and discharging same therefrom;

Figure 7 is a fragmentary detail section taken on the line 7—7 of Figure 3;

Figure 8 is an elevational view of the mold insert shown in Figure 5; and

Figure 9 is an elevational view showing a pair of cooperating complementary mold inserts for producing another form of casting.

The main frame of the particular machine illustrated in the drawings comprises a base section 10 supported upon suitable legs or standards 11. The base section 10 and standards 11 may be formed of cast iron or other suitable material. The two master mold plates for holding the molds are indicated at 12 and 13. One of these plates, i. e., the master mold plate 13, is relatively stationary. This relatively stationary

plate 13 is formed integral with an upright supporting member 14, and is supported in upright position thereby as shown. The supporting member or standard 14 is of angular and webbed or other suitable structural form at the bottom, and is bolted at 15 to the base section 10. The base section 10 is hollowed out at 16 to receive a removable tray or crucible 17 formed of graphite or other suitable material. This crucible is adapted to catch the overflow and waste metal in the operation of the machine.

A carriage 18 is mounted for sliding movement upon the top of the base section 10. Tongue and groove engagement is provided at 19 between this carriage 18 and the base section 10 (Figure 3) for guiding the carriage 18 toward and away from the mold plate 13. The cooperating portions of the base section and carriage 18 are fully machined, and the carriage may be formed of cast iron or other suitable material. The carriage 18 has an aperture 20 adapted to register with longitudinally spaced apertures 21 in the base section 10, and a pin 22 is provided for insertion through the aperture 20 and into any of the apertures 21 with which the aperture 20 is registered to lock the movable carriage 18 in any desired position along the base section 10.

A second carriage 25 is mounted for sliding movement upon the top of the carriage 18. Dovetail engagement is provided at 26 between this second carriage 25 and the carriage 18 (Figure 3) for guiding the upper carriage 25 upon the lower carriage 18 longitudinally toward and away from the mold plate 13. The cooperating portions of the carriages 18 and 25 are fully machined, and the upper carriage 25 may be formed of cast iron or other suitable material.

A handle 27 is provided for manually moving the upper carriage 25 longitudinally along the lower carriage 18 on the ways provided by the dovetail engagement at 26. The handle 27 is fixed upon the outer end of a cross shaft 28 which is turned by turning the handle. The shaft 28 is journaled in the carriage 18, and has a gear 29 fixed thereon to turn with the shaft 28. The gear 29 meshes with a flat bed gear or toothed rack 30 mounted on the under side of the top carriage 25, so that when the handle 27 is turned the action of the gear 29 on the rack or gear 30 will cause the upper carriage 25 to move toward or away from the mold plate 13.

Instead of manually turning the cross shaft 28, I contemplate the provision of power means for this purpose. I also contemplate automatically controlling the power means for moving the upper carriage 25 automatically to close and open the mold means. Where the machine is operated automatically, the automatic operation will preferably be timed to permit unloading or removal of the castings while the movable master mold plate is parted from the stationary master mold plate. I also contemplate automatically controlling the displacement delivery of the molten metal to the mold means so that this delivery of molten metal will be timed to take place when the mold is closed.

The upright and relatively movable master mold plate 12 is bolted at 32 to a generally elbow shaped arm 33, which arm 33 in turn is bolted at 34 to the top of the upper carriage 25. The movement of the lower carriage 18 provides for bringing the mold plate 12 into and out of the desired relation with respect to the matching mold plate 13 and for providing relatively great travel to free the mold plates from relatively

long objects. The movement of the upper carriage 25 provides for bringing the movable mold plate 12 into and out of engagement with the relatively stationary mold plate 13.

Adjusting bolts 36, threaded through flanges on the upper carriage 25 and into engagement with the mold plate 12, are adapted for adjusting this plate 12 into parallel relation and accurate registration with the mold plate 13 so that these mold plates and the casting molds carried thereby and the cooperating gates will match or fit perfectly when in closed relation when the plate 12 is in closed position. Further to insure perfect fitting of the matched mold plates, the plate 13 has guide pins 37 secured at 37' thereto, and these pins 37 have sliding engagement in apertured lugs 38 projecting laterally from the opposite sides of the mold plate 12 to guide the plate 12 into perfectly fitting engagement with the plate 13 and to prevent relative sagging between the mold plates.

The matched master mold plates 12 and 13 are formed of metal or other suitable material that is preferably a relatively good conductor of heat. Each plate is hollow and shaped generally to a four-sided hollow box-like form. The cavity 40 (Figure 4) within each plate 12 and 13 is provided primarily for holding and circulating water or other suitable cooling medium within the plate and around the bodies of the molds or mold holders which are in direct contact with the cooling medium, as will presently appear. This cooling hastens congealing or solidification of the hot metal. It is to be understood, however, that the metal will congeal or solidify with natural cooling and that, therefore, the cooling arrangement shown may be omitted within the scope of the broader aspects of the present invention. Moreover, if desired, the cavity 40 of the mold plates may hold a heating medium for applying heat to the molds to maintain the metal in the molds in molten condition until the desired filling of the molds is accomplished.

In the illustrated embodiment of the invention, the mold plates 12 and 13 are provided with a plurality of matched mold holders 42. Six of these mold holders 42 are shown in each of the mold plates 12 and 13, but the particular number of such mold holders in each mold plate may vary widely within the scope of the present invention. I contemplate one or more molds within the broader aspects of the invention.

Each mold holder 42 is of generally tubular form, provided at its mold carrying end with an integral annular flange or collar 43, and threaded externally at 44. The opposite end of each mold holder 42 is reduced and externally threaded at 45. The mold plates 12 and 13 have registering openings 46 and 47 through which the mold holders are inserted from the front sides of the respective mold plates and into the positions shown in Figure 4. The threads 44 on the mold holders have threaded engagement with the front side of the mold plate at the openings 46, but the reduced and threaded ends 45 pass freely through the openings 47 in the back wall of the mold plate. The mold holders are thus inserted into the mold plates from the front sides of the respective plates, and continue through the cavities 40 and through the back sides of the mold plates.

The outer surface of the front wall of the mold plate 13 is provided with a recess 50 concentric with each pair of aligned openings 46

and 47 for receiving the flanges or collars 43 on the mold holders 42, and also receiving adjusting nuts 51 threaded upon the threaded portions 44 of the mold holders. Suitable washers 52, beneath the nuts 51, seat upon the inner ends of the recesses 50 and seal the openings 46.

The outer surface of the front wall of the mold plate 13 is faced with a layer 54 of very good heat insulating material such as asbestos mill board, dolomite refractory, or other suitable material which is a very poor conductor of heat. A suitable material for this purpose is formed of asbestos and magnesia, the asbestos providing the desired heat insulating characteristic and the magnesia making the material resistant to high temperatures so that the facing will not break down or decompose under such temperatures. The facing 54 may be formed of any material having the desired heat insulating properties to accomplish the results which will presently appear. This facing may be secured to the outer surface of the mold plate 13 by screws (not shown), or in any other suitable or preferred manner.

In the illustrated embodiment of the invention, the mold members 60 are in the form of inserts preferably formed of metal or other good heat conducting material. The outer ends of the particular mold inserts shown are enlarged to seat upon the outer ends of the mold holders 42. These enlarged outer ends of the mold inserts fit in openings 61 in the heat insulating facing 54. The inner reduced ends 62 of the mold inserts 60 fit telescopically within the mold holders 42, and the mold inserts are readily removable so that they may be replaced or interchanged as desired.

As shown in Figure 5, pins 64, secured to the mold plate 13, project into the recesses 50, and are adapted to engage in openings in the nuts 51 to hold these nuts 51 against turning when the mold holder 42 is inserted into place. Thus, by grasping the opposite end of the mold holder 42 or engaging a suitable tool therewith, the mold holder may be turned, and this turning movement threads the mold holder axially through the nut 51 to dispose the outer flanged end 43 in position to seat the mold insert 60 with its outer end flush with the outer surface of the facing 54. After the mold holder 42 is adjusted into position to seat the mold insert 60 in the desired position, a lock nut 65 is threaded upon the opposite end of the mold holder to lock the same securely in place. The various mold holders may be adjusted selectively as desired merely by loosening the lock nuts 65 and turning the mold holders to adjust same axially to the desired position, whereupon they may be secured in adjusted position by tightening the nuts 65. Washers 67 are preferably interposed between the lock nuts 65 and the back surface of the mold plate 13 to seal the openings 47.

The two master mold plates 12 and 13 and the various mold holders 42 and mold inserts 60 in each of the master mold plates 12 and 13 are identical, except for the casting cavities 68 which may be alike or different, as desired, so that the foregoing description will suffice for all. In the illustrated embodiment, the mold holders are inserted before the insulating facing 54 is applied, but this may vary within the scope of the present invention.

Each mold insert has a casting cavity 68 for casting the metal object to the desired shape. 75

The present machine will handle all kinds of metals or alloys, such as aluminum, bronze, white brass, or any other metals or alloys, and is adapted for producing dense and homogeneous objects of any shape or size. The molds 60 shown in Figures 4 and 8 have the mold cavities 68 shaped to produce water pump impellers for a well known make of automobile. To provide an opening for receiving the shaft for the impeller, the molds 60 shown in Figures 4 and 8 are bored at 69 to support cores 70 of suitable core material in the casting operation. This may, of course, vary widely within the scope of the present invention. For example, the shaft 15 may be placed directly in the casting machine, with a knurled or otherwise roughened portion disposed in the casting cavity, and the impeller may be cast directly upon the knurled or roughened portion of the shaft. The double carriage 20 arrangement provides adequate movement for introducing and freeing relatively long members upon which castings may be formed.

The matching mold inserts shown at 72 and 73 in Figure 9 have complementary casting cavities 74 and 75 for producing a metal object of different shape. One of these mold inserts 72 is carried by a mold holder on one of the master mold plates 12, 13, and the other mold insert 73 is carried by the aligned mold holder on the other master mold plate. When the movable mold plate is closed into casting position, the cavities 74 and 75 make up together the complete cavity for casting the desired object.

The mold inserts 72 and 73 are interchangeable with the mold inserts 60, and mold inserts with other forms of casting cavities may be provided for casting objects of any desired shape or size. By using mold inserts with different casting cavities on the same mold plates at the same time, different objects may be cast in the same casting operation. The mold inserts may be readily removed and replaced or interchanged, and it is possible to change any one or more objects produced by the machine expeditiously and without changing the master mold plates.

The outer surfaces of the heat insulating facings 54 of the master mold plates 12 and 13 are provided with vertically disposed matching gates 78 open at the top, as indicated at 79, and closed at the bottom at 80 (Figure 2). These gates open into or communicate with upwardly inclined runners or gates 82 which, in turn, open into or communicate at their opposite ends with the casting cavities in the mold inserts. In Figure 2, communication between the gates or runners 82 and the casting cavities 68 is afforded through one of the spaces in which the blades of the impeller are formed, the outer ends of the casting spaces for the other blades of the impeller being closed by the surrounding refractory facing 54.

Instead of having a portion of the casting cavity open to the refractory facing 54, the cavity may be confined or enclosed wholly within the metal body of the mold insert, and matching openings may be provided as shown at 84 (Figure 9) for delivering the molten metal into the casting cavities from the gates or runners 82. In any event, the adjustable mounting of the mold holders 42 not only affords the adjustment already described, but provides for adjusting the molten metal receiving openings of the mold inserts into proper registration with the gates or runners 82.

Where the mold is cooled, water or other cool-

ing medium is supplied into the cavities 48 in the master mold plates 12 and 13 by a cooling medium supply line 88 having, for example, flexible connection at 89 with the cavity 48 in the master mold plate 13 and flexible connection at 90 with the cavity 48 in the master mold plate 12. The cavity 48 of each plate 12 and 13 is provided in proximity to the top thereof with air vent openings 93. Upright overflow pipes 94 within the cavities 48 of the respective plates 12 and 13 discharge through overflow or discharge lines 95.

In making up the mold inserts, these inserts are preferably machined from the centers of the cavities in the mold holders to fit the cavities of the mold holders. As already pointed out, the mold inserts are fitted into the cavities of the mold holders for use and are readily replaced by other mold inserts, as desired. These inserts enable any desired mold to be removed from any multiple or single set plate without disturbing the balance of the molds or the machine setting. Moreover, the locking and adjusting of the molds or mold holders are accomplished independently and without disturbing the machine setting in any way. The use of mold inserts with mold holders enables absolute accuracy and low mold cost. The features of adjusting and holding the molds and inserts and of adjusting the movable master mold plate are important aspects of this invention.

Instead of employing mold inserts in combination with the mold holders 42, the mold holders may have the casting cavities formed directly therein, within the scope of the present invention. This would eliminate the necessity of separate mold inserts, and in such case the mold holders 42 would be removed from any multiple or single set plate and replaced with other mold holders having different casting cavities to form different objects.

The right hand end of the machine as viewed in Figure 1 is provided with a metal heating furnace 98. This furnace 98 has a suitable burner 99 positioned below the container 100 for the molten metal. The burner 99, which may be an oil or gas burner or any other suitable burner, is supplied with fuel through a fuel supply line 102, and, for example, in the case of a gas burner, air may be admitted at 103. The fuel supply line 102 is provided with a control valve indicated at 104. The furnace 98 is supported in elevated position upon the base section 10 by uprights 105.

With the illustrated construction, the molten metal container 100 is positioned in close proximity to the mold means. The furnace 98 is covered as indicated at 106, and a suitable refractory lining may be provided as indicated at 108. The molten metal container 100 has a spout indicated at 110, which opens into a refractory lead or trough 112. This lead or trough 112 slopes downwardly through the refractory lining 108 and covering of the furnace, and its opposite end is positioned to discharge the molten metal into the open upper ends of the gates 78 when the mold is closed. The molten metal container 100 may be supported within the furnace in any suitable or preferred manner, as by means of diametrically opposite bosses or trunnions 114 which engage in slots 115 in the furnace.

For the purpose of delivering the molten metal to the mold, I provide a displacement plunger 116 (Figure 1) which is adapted to be lowered into the molten metal container 100 to displace the

molten metal therefrom and to be raised out of the container 100. The plunger 116 is pivoted at 117 to a link 118, which link is in turn pivoted at 119 to an operating lever 120. The lever 120 is pivoted at 121 to an arm or bracket 122 fixed, for example, to the furnace 98. The lever 120 is maintained in the position shown, with the displacement plunger 116 elevated by means of a spring 124 coiled, for example, about an arcuate guide 125 pivoted at 126 to the lever 120.

The particular lever arrangement shown provides one suitable means for manually operating the plunger 116. This means may vary widely within the scope of this invention, and, as already pointed out, the plunger may be operated automatically and in timed relation to the closing of the mold. When the mold is closed and the plunger 116 depressed into the container 100, the level of the liquid metal rises in the container until it reaches the level of the spout 110. The liquid metal will then flow out of the container through the trough or lead 112 and into the matching gates 78 of the mold. Upon entering the mold plate, it is distributed direct to the one or more mold inserts or mold members through the openings provided in the insulating facings of the master mold plates. When the mold receives all the metal necessary entirely to fill all of the impressions or casting cavities, the metal will rise and stand in the refractory lead, at which time the operator will make the necessary motion mechanically to cause the plunger 116 to rise up out of the container 100.

The speed at which the plunger is operated regulates the flow of metal from the container, and, as already pointed out, this displacement method in conjunction with the arrangement of the mold plates results in utilization of the force of gravity in filling the molds and permits accurately controlling the amount of metal delivered to the mold plates in accordance with that required properly to fill the molds. The displacement method minimizes the time and heat loss of getting the metal from the container to the mold plate, and oxidation of the metal caused by exposure to the atmosphere is reduced.

By its position in the opening 143 at the top of the furnace 98, the plunger 116 is subjected to the hot gases or heat of the furnace, so that it will not chill the molten metal in the container 100 when lowered into the same. The plunger 116 is preferably made of carborundum or of a combination of insulating and refractory material of the character employed, as the facings 54, cast into shape, or of other suitable material, so that the plunger will not be disintegrated or otherwise deleteriously affected by the hot metal, particularly by molten aluminum or any of its bronze alloys.

With the plunger displacement method of delivering the molten metal to the mold means of the machine, the plunger does not require a close fit in the molten metal container 100. If the plunger wears down, its operation may be adjusted at 118 to secure proper displacement of the molten metal from the container 100 when the plunger is lowered into the same. Moreover, with the utilization of the force of gravity in delivering the molten metal into the mold means, the danger of flashing of molten metal, particularly if the molds do not close tightly, is eliminated. When the molten metal is delivered to the mold means under high pressures, as commonly done heretofore in the art, this danger of

flashing of hot metal from the mold has presented a difficult problem.

As the molten metal passes through the openings in the refractory facings 54 of the master mold plate, heat loss from the molten metal is reduced or substantially eliminated by reason of the heat insulating character of these facings. This prevents chilling or solidification of the molten metal in the gate or runner means or elsewhere in its passage to the mold, and assures that the molten metal is delivered into the mold in the desired molten condition completely to fill the mold and produce good homogeneous and dense castings at all times. Moreover, the maintenance of the metal in molten condition in its passage through the gate and runner means eliminates cleaning of gates and runners from the finished work and clogging of the metal in its passage to the mold means. The arrangement of the master mold plates permits the molten metal to drain from the runners and gates in the heat insulating facings 54 when the mold plates are parted by moving the mold plate 12 away from the mold plate 13, and this molten metal which drains from the runners and gates in the insulating facings flows into the removable tray or crucible 11.

Where a cooling medium is held and circulated directly within the master mold plates 12 and 13, it will be noted that the mold holders 42, which are of good conducting material, are in direct contact therewith, and this, together with the good conductivity of the mold inserts 60, extracts the heat from the molten metal in the casting cavities 68. This cooling hastens the congealing or solidification of the hot metal in the casting cavities. At the same time, the insulating facings 54 prevent any cooling action upon the molten metal passing through the openings in these facings 54, with the advantages already set forth.

The large cooling bodies provided in the master mold plates of my present invention provide for rapidly and effectively dissipating the heat from the mold holders and mold inserts. This protects these parts against cracking or other injury under excessive temperatures during the operation of the machine.

It is to be understood that the metal will congeal or solidify in the mold cavities with natural cooling, and that the hollow formation and cooling medium may be omitted within the scope of the present invention. It is to be further understood that heat may be applied to the casting molds to maintain the metal in the desired molten condition until the casting cavities are completely filled. The top of the gate 78 in the facing 54 of the mold plate 12 may be provided with an upwardly extending funnel-like portion 140, if desired. The top of the furnace is shown as provided with a cover 142 having an opening 143 through which the plunger 116 operates. The facing plates 54 are preferably provided with notches, as indicated at 145 in Figure 2, to permit the escape of air or gas from the casting cavities so that there will not be any trapping of such air or gas in these cavities such as might impair the homogeneity of the castings.

In the operation of the machine, the mold is closed by moving the movable master mold plate 12 into closed and accurate matching engagement with the relatively stationary mold plate 13. The mold holders and mold inserts, as well as the gates and runners in the respective master mold plates, match accurately, and when the mold

is closed the plunger 116 is operated to discharge the molten metal into the mold by displacement. As soon as the mold cavities are filled and the metal in these cavities is set, the mold plate 12 is parted from the mold plate 13, and the overflow and waste metal in the openings in the face plates 54 drains into the crucible 11. Where the operation of the machine is automatic, it is timed to permit removal of the cast objects while the mold plate 12 is parted from the plate 13. The cycle of operation is repeated as often as desired.

I do not intend to be limited to the precise details shown or described.

I claim:

1. In combination, a master mold plate, a mold holder having screw threaded connection with said plate, a mold removably mounted in said mold holder, a heat insulating facing mounted on said mold plate and having an opening to receive said mold and gate means communicating with said opening for delivering molten metal to said mold, means for rotating said mold holder to adjust the position of said mold relative to the surface of said heat insulating facing, and means connected with the end of said mold holder opposite said mold for locking said mold holder in adjusted position.

2. In combination, a frame, a relatively stationary master mold plate on said frame, carriage means mounted for movement toward and away from said relatively stationary master mold plate, a relatively movable master mold plate mounted on said carriage means for movement to closed position relative to said first mold plate and adapted to be parted therefrom, readily removable casting molds on said mold plates, and heat insulating facings formed of a material of low heat-conducting capacity mounted on said mold plates and having cooperating gate means formed in said heat insulating facings for delivering molten metal to said molds.

3. In combination, a frame, a relatively stationary master mold plate on said frame, carriage means mounted for movement toward and away from said relatively stationary mold plate, a relatively movable master mold plate mounted on said carriage means for movement to closed position relative to said first mold plate and adapted to be parted therefrom, readily removable casting molds on said plates, heat insulating facings formed of a material of low heat-conducting capacity mounted on said mold plates and having cooperating gate means formed in said heat insulating facings for delivering molten metal to said molds, and means for adjusting one of said mold plates to provide matching relation of said plates and the casting molds and gate means thereon.

4. In combination, a frame, a relatively stationary master mold plate on said frame, a carriage mounted for movement on said frame toward and away from said relatively stationary mold plate, a second carriage mounted for movement on said first carriage toward and away from said relatively stationary mold plate, a relatively movable master mold mounted on said second carriage for movement to closed position relative to said first mold plate and adapted to be parted therefrom, casting molds on said mold plates, heat insulating facings formed of a material of low heat-conducting capacity mounted on said mold plates and having cooperating gate means for delivering molten metal to said molds, means for adjusting said casting molds in said plates and

for securing same in adjusted position, and means for adjusting one of said mold plates to provide matching relation of said plates and the casting molds and gate means thereon.

5. In combination, a mold plate having a cavity therein, said plate having aligned openings in the walls at opposite sides of said cavity, a tubular mold holder fitting through said openings, a threaded member held to said plate and having threaded engagement with said mold holder to produce axial movement of said mold holder by turning thereof, a nut having threaded engagement with said mold holder and cooperating with said plate to lock said mold holder in adjusted position, and a mold insert removably fitted in said holder.

6. In combination, a pair of relatively movable molds forming a mold cavity, cooling means therefor, complementary parts formed of heat insulating material carried by said molds and forming gate means communicating with said mold cavity, said parts being substantially non-conductive as regards the transmission of heat so that molten material in the gate means remains in molten condition after the metal in the cooled mold cavity becomes solid, means for parting said molds, and means for receiving the molten material flowing from said gate means when the molds are parted, said receiving means retaining the molten material from the gate means in a pool in which only the surface is exposed.

7. In a molding machine, a hollow mold plate having opposite walls, there being aligned aper-

tures in said wall and one of said walls having an enlarged recess about the aperture therein, a tubular mold holder disposed in said aligned apertures and having a flange at one end disposed in said recess, means adjustably fixing the position of said mold holder in said aligned apertures, and a mold insert removably disposed in the tubular mold holder and having a head disposed against said flange.

10 8. In a molding machine, a hollow mold plate having opposite walls provided with aligned apertures, one of said walls having an enlarged recess about the aperture therein, a tubular mold holder extending through said aligned apertures and having a head disposed in said recess and a threaded connection with said recessed mold plate wall, the flange end of said tubular mold holder having an enlarged interior bore and the opposite end having a smaller tool receiving bore, a mold insert having a shouldered head and a shank portion adapted to be disposed in said enlarged bore with the shouldered head disposed against the flange of said mold holder, a heat insulating facing secured to said one wall of the mold plate and having an aperture adapted to receive the head end of said mold insert, rotation of said mold holder serving to position the head of said mold insert substantially flush with the outer surface of said heat insulating facing, and means at said other end of the mold holder for locking the latter in adjusted position in the mold plate.

DONALD H. GARTH.
